UNITED STATES PATENT OFFICE.

GEORGE DONAHUE, OF HYDE PARK, MASSACHUSETTS, ASSIGNOR, BY MESNE ASSIGNMENTS, TO FREDERICK L. EMERY, OF LEXINGTON, MASSACHUSETTS.

CAR DOOR.

1,423,200.

Specification of Letters Patent.

Patented July 18, 1922.

Application filed September 13, 1910, Serial No. 581,851. Renewed December 26, 1919. Serial No. 347,634.

To all whom it may concern:

Be it known that I, GEORGE DONAHUE, a citizen of the United States, and a resident of Hyde Park, in the county of Norfolk, 5 State of Massachusetts, have invented an Improvement in Car Doors, of which the following description, in connection with the accompanying drawings, is a specification, like letters on the drawings representing 10 like parts.

This invention relates to doors and more particularly to trap doors such, for example, as are used to cover the space above the steps leading to the vestibules of passenger 15 cars.

Frequently, the platform of a station is on a level with the floor of the vestibule. In such cases the trap door covering the steps is used to bridge the space above the steps 20 extending from the vestibule floor to the side of the car. There is, however, always a space between the car and the adjacent edge of the station platform. This space is very dangerous and objectionable since passengers on 25 boarding or leaving the train are liable to make a mis-step into said space and be injured thereby. One of the objects of this invention is to provide a trap door which 30 will effectually bridge the space between the side of the car and platform and thereby eliminate the danger referred to.

The character of the invention may be best understood by reference to the following description of an illustrative embodiment thereof shown in the accompanying drawings, wherein:

Fig. 1 is a plan of a portion of an end of a car showing a vestibule equipped with doors embodying my invention;

Fig. 2 is a vertical section taken on line 2—2 of Fig. 1;

Fig. 3 is a section taken on line 3—3 of Fig. 1;

Fig. 4 on an enlarged scale is a detail of 45 a control device for the door;

Fig. 5 is a section taken on line 5—5 of Fig. 4; and

Fig. 6 is a transverse section taken on 50 line 6—6 of Fig. 5.

Referring to the drawings, 1 represents an end of a car having a vertical wall 2 and a vestibule platform 3 extending from the

end wall 2 to the end of the car and supported by beams 5 and 7 extending the width of the car and sills 9 extending longitudinally 55 of the car. At the opposite ends of the vestibule platform 3 are the usual steps 11.

To cover or bridge over the spaces extending from the edge of the platform to the side of the car above the steps 11 there may be 60 provided trap doors 13 adapted to be tilted from a vertical position extending parallel to the end wall of the car, as shown at the right of Fig. 1, down to a horizontal position to bridge the space above the car steps, 65 as shown at the left of Fig. 1.

One of the important features of the invention consists in the provision of means for automatically sliding the door in the direction of its plane to cause a portion 70 thereof to project beyond the side of the car to bridge the space referred to between the side of the car and the edge of a station platform. To this end each door is secured fast to a shaft 15 as by brackets 75 17 secured to the under side of said door and apertured to receive said shaft (Fig. 3). The shaft 15 is journaled in bearings 19 conveniently secured to the beam 7 referred to. 80

The shaft 15 is extended beyond the inner edge of the door 13 into a bearing or sleeve 21 somewhat larger than said shaft, the latter being journaled in a collar 22 contained within said sleeve and secured thereto. At a point spaced from the collar 22 the shaft 15 is provided with a flange 23 fast 85 thereon having a rotative and sliding fit in said sleeve 21. This sleeve may be conveniently secured by ears 24 to the beam 7 referred to, the sill 9 having a portion cut 90 away to receive said sleeve, as shown in Fig. 2.

To shift the shaft 15 axially to cause the door to extend beyond the side of the car and bridge the space between the latter and the station platform the sleeve 21 is provided with a cam slot 25 preferably of sinuous form and having a very slight pitch relative to the axis of said sleeve, said slot being adapted to receive a pin 27, herein projecting from the shaft flange 23 and preferably provided with a friction reducing roller 29. In some instances it may be desirable to provide said sleeve with a second 100

slot 31 shown in dotted lines in Fig. 4, which may be similar to the slot 25 described and may receive a roller 33 and a pin which may conveniently be a continuation of the pin 27 referred to.

In operation when the door 13 is in its up or vertical position the pin 27 will be at the right end of the slot 25 (Fig. 4). When the door 13 is tilted down to a horizontal position the pin 27 will follow through the cam slot 25 and thereby shift the shaft 15 axially to the left of Fig. 4 and cause the door to project beyond the side of the car. The engagement of the follower roller 29 with the ends of the slot 25 may be utilized to limit the movements of the door 13 although other stop means may be used, if desired.

The door when in its up position may overlap the edge portion of the vestibule platform somewhat, but when in its down tilted position, the edge of the door may rest on a ledge 34 (Fig. 2) of said platform thereby bringing the surface of the door on a level with said platform.

To tend to maintain the door in its up or vertical position and counterbalance the effect of gravity thereon, the shaft 15 may be extended to the right of Fig. 4 beyond the sleeve 21 and be provided with a tension device herein in the form of a helical spring 35 encircling the shaft 15 and having one end abutting the collar 22 referred to and its opposite end abutting the end of a casing 39 secured to the shaft 15 by a nut 41 and adapted to slide along the exterior of the sleeve 21. When the shaft 15 is shifted to the left of Fig. 5 as on the tilting of the door 13 from its vertical to its horizontal position the spring 35 will be compressed against the shoulder 37 and the energy previously stored in said spring will tend to return and maintain the door in its up position. To hold the door in its down position a spring pressed latch 42 may be provided which will automatically lock the door in its down position. When this latch is released the door will spring up sufficiently above the level of the vestibule platform to permit it to be grasped and tilted up to its vertical position, said spring contributing to this movement. To hold the door in its up position a spring catch 43 (Fig. 2) may be provided if desired.

By my invention it is not necessary to give the door a separate manual movement in order to slide it outwardly beyond the edge of the car to bridge the space between the latter and the station platform but, on the contrary, this movement is effected entirely automatically as an incident to the rocking of the door from its vertical to its horizontal position. By the device described a considerable amount of shifting movement of the door sufficient for the purpose de-

sired is had merely by the tilting of the door through an angle of 90°.

The device is simple in construction and operation, will not get out of repair and requires no other attention than an occasional oiling. Furthermore, the device is extremely compact and occupies a very small amount of space and is concealed from view beneath the vestibule platform.

While I have described my invention for purposes of illustration in connection with a car, it will be understood that it has other fields of application.

Having described one embodiment of the invention, without limiting myself thereto, what I claim as new and desire to secure by Letters Patent is:

1. The combination with a car platform, of steps leading therefrom, a swinging tread door for bridging a space above said steps between said car platform and a station platform, a horizontal hinge for said tread door, and means outside of said space to shift said door to and from its active bridging position.

2. The combination with a car platform, of a swinging tread door for bridging the space between said car platform and a station platform, a horizontal hinge for said tread door, and means outside of said space to shift said door to and from its active bridging position.

3. The combination with a car platform, of a swinging tread door for bridging the space between said car platform and a station platform, a horizontal hinge for said tread door, and means located beneath the car platform to shift said door to and from its active bridging position.

4. The combination with a car platform 105 of a tread door 13 for bridging the space between said car platform and a station platform, a shaft 15 connected to said door, and means 21, 25, 27, 29 located outside of said space for shifting said shaft axially to 110 adjust said door to and from its active bridging position.

5. The combination with a car platform, of a tread door for bridging the space between said car platform and a station platform, a shaft connected to said door, a sleeve receiving a portion of said shaft, and means within said sleeve cooperating with said shaft to shift said door to and from its active bridging position.

6. The combination with a car platform of a tread door for bridging the space between said car platform and a station platform, and means to shift said door to and from its active bridging position comprising 125 a sleeve having a cam slot therein and a shaft connected to said door, projecting into said sleeve and having an element working in said cam slot.

7. The combination with a car platform 130

- of a tread door for bridging the space between said car platform and a station platform, and means to shift said door to and from its active bridging position including 5 a sleeve having cam slots therein and a shaft having elements working in said slots.
8. The combination with a car platform of a tread door for bridging the space between said car platform and a station platform, and means to shift said door to and from its active bridging position including 10 a sleeve having a cam slot, a shaft having an element projecting into said cam slot and a roller on said element working in said cam 15 slot.
9. The combination with a car platform of a tread door for bridging the space between said car platform and a station platform, and means to shift said door to and 20 from its active bridging position including telescoping members and cam means for causing one to move axially of the other.
10. The combination with a car platform of a tread door for bridging the space between said car platform and a station platform, and means to shift said door to and from its active bridging position including 25 telescoping members, one connected to said door and the other connected to the car, and cam means for shifting said door member axially of the other member.
11. The combination with a car platform of a tread door for bridging the space between said car platform and a station platform, and means to shift said door to and 30 from its active bridging position including telescoping members, cam means for shifting one of said members in one direction, and spring means cooperating with said cam 35 means to shift said member in the opposite direction.
12. The combination with a car platform of a tread door for bridging the space between said car platform and a station platform, and means to shift said door to and 40 from its active bridging position including a shaft connected to said door, a sleeve having a cam slot therein, an element on said shaft working in said slot, and a coil spring 45 tending to shift said element toward one end of said slot.
13. The combination with a car platform of a tread door for bridging the space between said car platform and a station platform, and means to shift said door to and 50 from its active bridging position including a sleeve having a cam slot and a bearing therein, a shaft in said bearing having an 55 element working in said slot, and a coil spring encircling said shaft and reacting against said bearing for urging said element toward one end of said slot.
14. The combination with a car platform of a tread door for bridging the space between said car platform and a station platform, and means to shift said door to and 60 from its active bridging position including a sleeve having a cam slot therein, and a shaft having an element working in said slot, the extent of movement of the door being determined by the length of said slot.
15. The combination with a car platform 65 of a tread door for bridging the space between said car platform and a station platform, a bearing secured to the car, a sleeve 70 secured to said car and having a cam slot 25 therein, and a shaft 15 journaled in said bearing and sleeve and having an element 29 working in said slot.
16. The combination with a car platform, of steps leading therefrom, a tread door for 75 bridging the space above said steps between said car platform and a station platform, and cam means for automatically shifting said door to its active bridging position as it is rocked down to the plane of said car 80 platform and for automatically withdrawing said door from said position as it is rocked from the plane of said platform.
17. A combination with a car platform of 85 steps leading therefrom, bridging means for bridging a space between said car platform and a station platform, a pivot for said bridging means and means operatively connected to said pivot and outside of the space above said steps to shift said bridging means 90 to and from its active bridging position.
18. A combination with a car platform of 95 steps leading therefrom, bridging means constructed to be projected laterally from the car body toward an adjoining station platform to bridge a space between the same, a pivot for said bridging means and means operatively connected to said pivot removed from the space above said steps and out of contact with the person or clothing of a 100 passenger using said steps to project and withdraw said bridging means into and from active bridging position.
- In testimony whereof, I have signed my name to this specification, in the presence of 110 two subscribing witnesses.
